UNITED STATES PATENT OFFICE.

CHARLEY OFERREL DEVILBISS, OF DERRAHS, MISSOURI.

CARPET-STRETCHER.

SPECIFICATION forming part of Letters Patent No. 722,216, dated March 10, 1903.

Application filed May 12, 1902. Serial No. 106,978. (No model.)

To all whom it may concern:

Be it known that I, CHARLEY OFERREL DEVILBISS, a citizen of the United States, residing at Derrahs, in the county of Lewis and State of Missouri, have invented a new and useful Carpet-Stretcher, of which the following is a specification.

This invention relates to devices employed for the purpose of stretching carpets and the like; and it consists in certain novel features of construction, as hereinafter shown and described, and specified in the claims.

In the drawings illustrative of the invention, Figure 1 is a perspective view of the device. Fig. 2 is a vertical sectional elevation.

The device consists in an operating-handle 10 of any suitable length, having a T-head 11 attached to it at one end and supported in position by brackets or braces 12 12^a, the T-head being provided with a series of teeth 13 to enable it to grip the carpet. This T-head 11 may be of any length, and the points or teeth 13 of any suitable length and spaced apart to any suitable distance to enable them to properly engage the carpet. Attached by brace-arms 14 14^a to the handle 10 at 14^b 14^c is another "head" 15, provided with spikes or teeth 16 similar to the teeth 13, but not necessarily so many of them. The head 15 is thus free to swing upon its pivotal points 14^b 14^c, as will be understood.

Pivotaly connected to the handle 10 at 17 are spaced bars 17^a 17^b, and pivotaly supported at 18 between the spaced bars 14 14^a is a curved arm 18^a, pivotaly connected at its inner end at 19 between the inner ends of the spaced bars 17^a 17^b and with its outer end extended beyond the bars 14 14^a and turned off laterally to provide a foot-rest 18^b. The inner extremity of the arm 18^a is turned off laterally at 18^c to form a lip which extends over the upper surface of the bar 17^a beyond the pivot 20 to form a stop to limit the downward movement of the arms. The jointed arms 18^a and 17^a 17^b are so disposed that the pivotal line 19 will fall below the line between the pivots 17 and 18, so that when the device is extended as in the drawings they will be locked apart, as will be readily understood, and can be released only by moving the bars upward at their pivotal points 19. This upward movement and the con-

sequent releasing of the device will be readily accomplished by depressing the end 18^b by the foot of the operator.

In using the device the head 15 is inserted into the floor after one side of the carpet has been tacked down and the end 18^b depressed and the handle 10 adjusted to bring the head 11 in close proximity to the head 15 and inserting the teeth 13 in the carpet. Then by depressing the handle and extending the head 11 away from the head 15 the carpet will be stretched, as will be readily understood, this action bringing the arms 18^a and 17^a 17^b into their locked position, as shown in the drawings, and thereby holding the portion of the carpet stretched until it can be tacked. This action can be repeated whenever required to stretch the carpet to any required extent and at any required point in the room.

This makes a very complete, simple, and effective implement for the purpose required, easily operated, and requiring the expenditure of very little strength to manipulate it.

The implement may be constructed in any size or form and may be made wholly of metal or partially of metal and partially of wood.

The proportions may be modified and altered without affecting the principle of the invention or sacrificing any of its advantages.

Having thus fully described my invention, what I claim is—

1. A carpet-stretcher comprising a handle member and a fulcrum member, pivotaly united and provided with spurs at their free ends, and a jointed foldable brace comprising pivotaly-connected members having pivotal connection at their free ends with the said handle member and the said fulcrum member, one of said brace members being provided with a stop to limit the movement of said foldable brace in a downward direction.

2. In a carpet-stretcher, the handle having spurs upon its lower end, a fulcrum member movably connected by one end to said handle and having spurs upon its free end, bars movably engaging said handle, a bar movably engaging said fulcrum member and pivotaly united by its free end to the free end of said handle-bars, and extended by its other

end beyond said fulcrum member, substantially as described.

3. In a carpet-stretcher, the handle having laterally-extended lower end, L-bars uniting said lateral extensions and said handle, spurs extended from said extended end, spaced fulcrum-bars movably engaging said handle on opposite sides, and extended laterally in opposite directions, a bar secured to said oppositely lateral extensions and having spurs extending therefrom, a lever-arm pivotally secured between said spaced fulcrum-bars, spaced lever-arms pivotally secured between said L-braces and said handle, and extended inwardly and pivotally secured upon opposite sides of said fulcrum lever-arm, substantially as described.

4. In a carpet-stretcher, the handle having laterally-extended lower end, L-bars uniting said lateral extensions and said handle, spurs extended from said extended end, spaced lever-arms movably secured between said L-bars and said handle, spaced fulcrum-bars movably engaging said handle on opposite sides and extended laterally in opposite directions, a lever-arm movably secured by one end between said spaced fulcrum-bars and extended inwardly and pivotally engaging the free ends of said spaced lever-arms, and extended outwardly to afford a foot-lever means, substantially as described.

extended inwardly and pivotally engaging said spaced handle lever-arms and having a lip extended laterally in engagement with one of said spaced lever-arms, substantially as described.

5. In a carpet-stretcher, the handle having laterally-extended lower end, L-bars uniting said lateral extensions and said handle, spurs extended from said extended end, spaced lever-arms movably secured between said L-bars and said handle, spaced fulcrum-bars movably engaging said handle on opposite sides and extended laterally in opposite directions, a lever-arm movably secured by one end between said spaced fulcrum-bars and extended inwardly and pivotally engaging the free ends of said spaced lever-arms, and extended outwardly to afford a foot-lever means, substantially as described.

In testimony that I claim the foregoing as my own I have hereto affixed my signature in the presence of two witnesses.

CHARLEY OFERREL DEVILBISS.
